United States Patent Office.

S. B. ROWLEY, OF PHILADELPHIA, PENNSYLVANIA.

Design No. 2,840, dated November 26, 1867.

DESIGN FOR THE BODY OF A JAR.

The Schedule referred to in these Letters Patent and making part of the same.

TO ALL WHOM IT MAY CONCERN:

Be it known that I, S. B. ROWLEY, of Philadelphia, county of Philadelphia, State of Pennsylvania, have invented or produced a new and original Design for the Body of a Jar; and I do hereby declare that the accompanying drawing and the following explanation thereof form a full, clear, and exact description of the said design.

In the accompanying drawing, A represents the body of a jar, which is rounded near the lower edge, (at x,) and which gradually diminishes in diameter from the line y y to the upper end.

I claim the design for the body of a jar, substantially as shown in and by the accompanying drawing.

In testimony whereof, I have signed my name to this specification in the presence of two subscribing witnesses.

S. B. ROWLEY.
